CONTAINER

Herman Samuel Zaikaner, New York, N. Y.

Application February 24, 1948, Serial No. 144,689

Term of patent 7 years

(Cl. D44—1)

To all whom it may concern:

Be it known that I, Herman S. Zaikaner, a citizen of the United States of America, residing at New York city, in the county of New York and State of New York, have invented a new, original, and ornamental Design for a Container, of which the following is a specification, reference being had to the accompanying drawing, forming a part thereof.

In the drawing:

I claim:

The ornamental design for a container, as shown.

HERMAN SAMUEL ZAIKANER.
